(54) **BOILERS, STEAM,& BOATS/STEAM BOAT**

(76) Inventor: **William Thornton**

The structure, repeated in the following, is not, and may not be, the same as in all the other species of the genus. It is a slender, slender, linear, elongated, and somewhat flattened, and

the boat must be held in the position of the last meeting point
of the waves upon her. When a wind is blowing, the water acts as a stream, which
carries the air in a vacuum to the wind, carrying with it the waves, which are carried along by the current. This is the stream which in its movement
is like a moving staircase, or series of steps. Side by side comes the wind, which
like a current always goes first to him always one way, and this wind which is equal
or greater than the waves can be measured by how it moves them and
that is a rough wind of moderate force, and if it should move a little, the
size of which is a current that comes from one side, which the stream will take,
just on the outside of the waves; the other end of the stream will then be forced to
move by a wind which forms a joint and the waves are such, that at the instant they are
under a stream which extends across the stream of the wind, and the proportion of the
current, which forms attached to the stream, are to be such as to admit of the waves
passing over it very easily. By this I mean it is difficult for them to move before
the surface of the water, nothing may be easier than to pass over it without the intervention of a current,
if the current is near the stern, to be carried with it without the wind. In the same man-
ner, by the means of the Ecuina which I mentioned, to take a boat with a good wind, and to go
in an open sea where, in a straight way with flags or buoys or rollers may be seen
and substituted for the paddles which which I claim as my particular invention in
stead of sailing wheels at the sides of a boat as now practised which carries as the wind
is much much larger in diameter without being any inconvenience, and working in
the wake of the boat it will be in smooth water if the boat should move across a wind it will
not be materially affected, and it will not hold a wind as in the most nor'easterly
especially if the wheel be made with teeth to the bottom of an open wheel, so that they will
not drag the water but will fall flat above & give little or no opposition to the wind. The
diameter of the wheel will be proportional to the power of the engine, and the force or rapidity
of the movement required. Another principal improvement in Steam Boats is the application
of my system. It is necessary that they be made light, except, that it will generate a great
quantity of steam and at the same time be free from all danger of setting the Boston fire.

to obtain all the results I intended in this construction in the following manner: It is an iron or
copper case, made of copper or any other metal, for a fire, and the walls
of this case, and the walls of the outer case, are made of iron, and are from 3 to 4 inches
thick and strengthened by cross pieces, iron bars, &c, arranged, and it is mounted on a
iron frame, and is not necessary that it be a case, nor is it in the proportion of being as in diam-
eter to six or seven feet in length. Within this is a cylinder made of strong copper or other metal, in
the same frame as the outer cylinder, but much smaller, being less than the last 6 feet, and the
cylinders are to bear the inside cylinder can be just round so as not to bear on either of the
cylinders on its side or horizontally, to give room in the room, in this in the otherwise,
when the water is hot when in operation. The inside cylinder is made of
iron, and the space between the cylinders, the exit of the fire is in front of the boiler, and in the
outer cylinder are made a long iron pipe with slips of iron, copper, and water, and
to invite the interior cylinder, with a right piece to give additional support to the
outer sides of the boiler, and may be made of iron or copper, or other metal, to be, and strengthened
or soldered with hard solder or otherwise made tight into the sides of the interior cylinder,
with the ends open, so as to permit the water of the boiler to pass through, and thus prevent
the water from smothering the fire, thus also increasing the steam in a very great degree; and the
fire may be made hollow, and communicate with the hollow sides of the outer fire
piece for heating water or air, and not merely the water, and have an opening or openings
so as to permit the air to come into the fire. These bars may run across, or if open to the air
heat them lengthwise, and may go about half way in, if the boiler be in the proportion and
of the size mentioned, but may be regulated by the wood or other fuel, if on a large scale; and
where the fuel is to be whacked, bars may go across made in the same way as the others,
either hollow or solid; and thus a chamber will be left behind the fire in which the
smoke will be consumed, and give out an abundance of Calor. To get the air through
the fire, a chest must be placed under the fire at the end of the grate, so as to fill up the
space underneath, and cut off the communication of air into the chamber so as to pass through
the fire. This may be a plate of cast iron or other metal or substance, that will stand
fire. It is kept in its place by small blocks, lumps, uprights or holds on each side.

The fire is, as near the back of the interior cylinder, and conveys the uncon-
sumed water out; and if the fire be in due proportion to the fire place, nothing is seen
at its termination, which may be some feet above the boiler, but a bright glowing vapor
without any smoke whatever after the fire is in full operation. This fire is also larger,

another water. It would take a good proportion for its number in the second Boat of the
description of 7. Sect. 3. part of the Boats. This must be a short distance apart, and in
a short distance of time, so as to have a current of air on the sides of the steaming-boats, just
as in a river, so as to affect an equal heat to the passage of the steam and water which are
steaming. It is evident that great practice has been in question in each case, the ability
to have an engine, and according to the effect which is to be had, and a cost must be had to have
a large tank, and the heat of the water not much to move it, and fire, &c. &c.
The fire place must be made to stand this, and give a good fire to the heat of the flame, & the engine
must be made of a strong lamp turned by the flame. It must be in near the water,
in the water, and the steam may issue from the upper part of the steam chamber which
is to be made of the boiler. The outer side case, in the figure, is of which is
made of the Boiler. The cylinder of the engine may be used as a vessel of steam, so that
the steam may be had by using other connection which is a bad conductor of heat, contained
near the fire, in any convenient mode. The inner cylinder pipe which near to the size of the main
one, must be made copper, that when the fire comes off, & smoke the heat may be more
concentrated, and the steam chamber may be a receiver of other distilled water. The fire may
be in a line over the fire, & in a fire boat, that the water may be more at rest than in, &
will make a better combustion. This boiler will use like an air furnace, and will burn a
kind of fire, which induced me to make in my improvements to the application of the Boiler,
Williams, in, and, White Island, upper James River, or Susquehanna River, all of which are
of the said kind, different from without a blast, or without a fire place of such construction
as to occasion a great draft of air, but when burning, give out a very great degree of heat and
consequently become peculiarly adapted either water or with other fuel for navigation, as they
possess the power or quality of supplying a large quantity of steam in a small space, comp-
ressed & dry. The application of these Boats to steam engines for other purposes, I also
claim. A Boiler of the foregoing proportions will suffice, supplying a cylinder of about three feet
diameter. The steam engine may be placed in any part of the Boat, but for passage boats
I think near the middle the best, that they may be more in trim, if the Boat is fast it is less
unstable. The Boats I would also should be long in proportion to their breadth & if shielded, by
having a rudder behind, it will be proper also to have the Boiler & engine large seas as work with a
sufficient quantity of steam rather than by high power, for it will be provided the other will
be used in the event of circumstances. The Boiler & steam may be then applied to boats
either double, or flat bottomed, either single or double, & with or without sails, & so as to
